COMPASS

William W. Stanfield, Largo, Fla.

Application May 7, 1940, Serial No. 333,819

2 Claims. (Cl. 33—30)

This invention relates to improvements in draftsman's tools, and particularly to improvements in compasses, with more particular reference to such compasses as are known as beams compasses.

An object of the present invention is to provide a compass that is particularly equipped for use in designing ovals and accordingly is adaptable to the needs of all classes of craftsmen, especially such as are engaged in the designing of "neon" and various other types of signs.

A further object of the invention is to provide a compass of this character characterized by simplicity of construction and use and which will have a wide range of usefulness rendering it adaptable to various kinds and sizes of work.

The invention together with its objects and advantages will be best understood from a study of the following description taken in connection with the accompanying drawings wherein:

Figure 1 is a perspective view illustrating a preferred form of the invention.

Figure 2 is a perspective view of an extension marker bar.

Figure 3 is a perspective view of a pair of rods forming part of the invention.

Figure 4 is a detail sectional view taken substantially on the line 4—4 of Figure 1.

Figure 5 is a perspective view illustrating a modified form of the invention.

Figure 6 is a plan view illustrating the use of the form of the invention shown in Figure 5 in scribing an oval.

Figure 7 is a perspective view of a holder for a marking instrument, and

Figure 8 is a perspective view of a third pair of rods to be used in accordance with the present invention.

Referring in detail to the drawings, and particularly to the form of the invention shown in Figures 1, 2 and 4, it will be seen that in this form of the invention the compass comprises an extension frame embodying a pair of relatively flat oblong bars or plates 5—5, each of which is provided at one end thereof with a head 6 that extends upwardly from its bar 5 and terminates in a pair of pointed legs 7—7 which may be used to pierce the board upon which the drawing sheet is placed to anchor the frame in position thereon, or may be equipped with feet 8 of cork or other suitable material so as not to pierce, scratch or otherwise mar the surface upon which the device is placed.

Further the frame embodies a channel member 9 which slidably accommodates in the channel

thereof the plates 5 and which is provided with slots 10 coacting with threaded openings 11 to accommodate screws or other fastening elements through the medium of which the plates 5 at the desired position of adjustment relative to one another and to the channel member 9 may be secured to the end that the frame may be secured at any desired position of extended or retracted adjustment. Thus in this connection the frame may be extended to a length as to accommodate a pair of guide rods 12; or extended to its full length to accommodate a pair of guide bars 12a; or may be retracted to the extreme of such retraction for accommodating a pair of relatively short guide rods 12b shown in Figure 3.

Also in accordance with the present invention the channel member 9 intermediate its ends is provided with an aperture to receive a pivot element 13 that extends through the center aperture 14 of the channel 9 and through aligned openings 11 in the overlapping ends of the plates 5 for securing said plates 5 and channel member 9 in assembled position and at the desired position of adjustment; the pivot screw 13 having a threaded terminal that threads into an opening 11 in the lower plate 5 as shown in Figure 4. In this connection it is to be noted that the openings 11a in the overlapping plate 5 are of larger diameter than the openings 11 in the lapped plate 5, the openings 11 in the plate 5 being threaded, while the openings 11a are not threaded.

Further in accordance with the present invention there are provided a pair of coextensive ratio bars 14 and 15.

The ratio bar 14 at one end thereof is bent laterally as at 16 and then inwardly as at 17 in parallelism with the bar 14, and the inwardly directed extremity 17 of said bar is apertured to accommodate the pivot element 13 so that said ratio bar 14 is free to rotate about the pivot element 13.

The ratio bar 15 at one end thereof is similarly formed as at 18 and 19, and the extremity 19 of the ratio bar 15 is provided with a squared aperture to receive a squared shoulder 20 of a bolt 21.

The bolt 21 extends upwardly through a slide block 22 that is provided with a pair of through openings 23 to accommodate the rods of the pair of rods 12, or the rods of the pair of rods 12b, or the rods of the pair of rods 12a, depending upon which pair of rods are used; the use of the selected pair of rods being dependent, of course, upon the desired length of the frame; it being noted in this connection that the double-ply heads 6 of the bars 6 have the innermost plies thereof suitably aper-

tured to accommodate the extremities of the bars of the selected pair of bars 12, 12a, or 12b, as the case may be.

Adverting again to the ratio bar 14, it will be seen that the same is provided with a longitudinal series of threaded openings 24 with which align the openings of a series of openings 25 in the ratio bar 15, and these ratio bars 14 and 15 are pivotally connected together at the desired point in the length of the respective bars through the medium of a pivot element 26, the extremity of the shank of which is threaded to threadedly engage in a selected opening 24.

Connected rigidly with the ratio bar 15 so as not to rotate relative thereto, and through the medium of the aforementioned screw 21 is a graduated marker bar 28, the same, adjacent one end thereof being provided with a squared opening to accommodate a squared shoulder 27 on the bolt 21; the apertured ends of the marker bar 28 being positively secured in engagement with the bolt 21 through the medium of a nut 29 threaded on the extreme upper end of the bolt 21.

The marker bar 28 is graduated as at 28, and the ratio bar 15 is graduated as at 29a, the graduations being in terms of inches and fractions thereof.

Also, in accordance with the present invention there is provided a holder for a marking instrument such as shown in Figure 1 and indicated by the reference numeral 30.

The holder shown in Figure 1 and indicated by the reference numeral 31 is in the form of a split sleeve which, at the edges thereof formed by the split, is provided with apertured extensions 32 to which is pivoted a lever 33 that when swung downwardly to the position shown in Figure 1 tends to cause the sleeve to contract about the marking element 30 for holding the latter securely within the sleeve of the holder 31. At the upper end thereof the holder 31 is provided with a spring clip 34 that engages the marker bar 28 as shown in Figure 1 so as to permit the holder 31 to be easily slid longitudinally of the marker bar to the desired position of adjustment thereon.

For accommodating a larger marking instrumentality there may be substituted for the holder 31, a holder such as shown in Figure 7 and indicated by the reference numeral 35. The holder shown at 35 embodies a pair of spring-biased, hinged clamping jaws 36 and a channel-shaped suspension element 37, the latter adapted to accommodate in the channel thereof the marking bar 28 in a manner to suspend the holder from the marking bar and to permit the holder to be readily positioned at the desired position of adjustment on the marking bar.

To use the device in scribing either a circle or an oval, and after the parts have been assembled, the device is positioned on the drawing paper or the like so that the pivot element 13 will be at the center of the figure to be scribed. When this positioning has been accomplished the parts are so positioned that the bolt 21 will be directly in vertical alignment with the pivot element 13.

Depending upon the diameter of the oval or circle to be scribed, the marker 30 is positioned at the desired and proper position on the marker bar 28 and the screw 26 is set opposite the proper graduation on the ratio bar 15 for pivotally connecting said bar 15 and bar 14.

The operator then moves the marker bar 28

to the right or left as the case may be, the ratio bar 14 swinging about the pivot element 13 and the ratio bar 15 swinging about the screw 26 as a pivot permitting the marker bar 28, always in alignment with the ratio bar 15, to move as required for a complete scribing of the circle or oval as the case may be.

Further in accordance with the present invention, and to prevent retrograde movement of the ratio bar 14 there is pivoted on the part 16 of said bar a double-acting dog 38 cooperable with a circular series of apertures 39 provided on the channel member 9 circumjacent the opening provided therein for accommodating the pivot element 13.

Also in accordance with the present invention there is provided for use as an extension of the marker bar 28 an extension marker bar 28a.

For detachably connecting the marker bar extension 28a with the marker bar 28 the latter at its free extremity is provided with an upstanding projection 40 to be engaged in a selected opening 41 provided in relatively spaced relation in the bar extension 28a, while the bar extension 28a at one end thereof is provided with a hook-like projection 42 to engage in a selected one of a series of spaced openings 43 provided therefore in the marker bar 28. Thus by the use of the extension 28a the complete marker bar may be extended or retracted to the length desired, and as the nature and size of the work may require.

In the form of the invention shown in Figure 5, the invention comprises a frame 5a in the form of an oblong channel block in the channel of 35 which is fitted a channel rail 44, the channel bar 5a being formed of a plurality, in the present instance 3 complementary and aligning sections, and the channel rail 44 being also composed of a plurality, in the present instance 3, channel rail 40 sections, one of the sections being of greater length than either of the two remaining sections so that said one section will overlap the joints between the sections of the frame 5a when the three sections of the frame are used.

Thus by eliminating any one or more of the sections thereof the frame 5a may be decreased in length, and of course only the required number of sections of the rail 44 will be used with the increased or decreased length of the frame 50 5a.

Slidable in the channel rail is a block 45 which corresponds with the slide block 22, hereinbefore described.

However, in this form of the invention the 55 marker bar, indicated by the reference numeral 46 and the ratio bar 15a corresponding to the hereinbefore described ratio bar 15, are integral one with another and at the junction of the bars 46 and 15a the same are pivoted to the block 60 45 as at 47.

Also in accordance with this invention there is provided a ratio bar 14a, corresponding to the hereinbefore described ratio bar 14, and this ratio bar 14a is pivoted to the frame 5a intermediate the ends of the frame, regardless of the length of the frame, as at 48.

Ratio bars 14a and 15a are each provided with a longitudinal series of apertures, the apertures in the bar 14a being threaded to accommodate 70 the threaded end of a pivot screw 49 corresponding to and functioning in substantially the same manner as the pivot screw 26. Thus it will be seen that the pivotal connection between the ratio bars 14a and 15a may be adjusted as found 75

desirable and as will be clear from a study of Figures 5 and 6.

Also in accordance with the use of this invention there will be provided for sliding engagement with the marker bar 46 a marker holder 31 or 35 as found desirable for carrying the usual marker 30.

In Figure 5 is illustrated the manner of using this form of device for drawing arcuate lines of such magnitude as would be difficult with other compass means in confined spaces, while in Figure 6 is illustrated the manner of using such form of device for drawing an oval.

It will also be appreciated that by reason of the connection between the marker bar 28 and the bolt 21, characterized by the shoulder 27, marker bar 28 may be connected with the ratio bar 15 at any set angle relative thereto, instead of merely in substantial alignment therewith, and as may be desired for the making of various forms of ovals without changing the position of the frame part of the device.

Also with this device ovals of great magnitude may be drawn by simply placing the pivot 13 in an opening 11 adjacent one end of the frame 5, and simply by swinging the end of the base frame around after the first half of the oval has been drawn, and leaving the pivot 13 in the same relative position.

It will also be understood that in order to make possible the drawing of ovals in a direction opposite to that shown in Figure 5, marker bar 46 may be positioned to extend in a direction opposite to that shown in Figure 5 by engaging the pivot 47 in the slide 45 with a selected opening in the ratio bar 15a and of course making the necessary adjustment in the pivotal connection between the ratio bars 15a and 14a.

Further in connection with the use of the holders 31 and 35 for a marking element, it is to be understood that these holders may be so constructed as to permit the marking element to extend above and below the marking bar.

It is thought that a clear understanding of the construction, manner of assembly, uses, and many advantages of a compass of this character will be had without a more detailed description; but in this connection it may be explained that

to my knowledge prior art devices in this class have been confined as to construction, utility, etc., to needs within the scope of the drafting board, whereas I, having knowledge of the more extensive needs and uses of a compass, especially by designers of large work, have endeavored to provide an adjustable construction of compass which can be easily manipulated and can be used with facility in designing work from close to its narrow base to an extensive magnitude far greater than the capacity of known prior art devices have permitted.

It is also to be understood that while I have herein shown and described a preferred embodiment of the invention, it is not intended to restrict the invention to the precise details herein shown and described, other than as may be required by the state of the prior art and scope of the appended claims.

Having thus described the invention what is claimed as new is:

1. In a draftsman's compass, an elongated frame, a rod extending parallel to the frame and supported in an upper position thereon, a block slidably supported by the rod, a pin passing vertically through the block and supported for rotary movement therein, a pair of ratio bars each having a hooked end, the hook of one bar extending downwardly, a pivot pin passing through the hook of this bar into the frame, the hook of the other bar extending upwardly and fastened to the lower end of the pin in the block, a pivot pin for pivoting the outer portions of the two bars together, means for adjusting the pin last mentioned longitudinally of the bars and a marker bar fastened to the upper end of the pin carried by the block forming an extension of the ratio bar which is connected with the block.

2. In a draftsman's compass, a base, a ratio bar having one end of U-shape to provide a long limb and a short limb, means pivotally connecting the short limb with the base, a dog pivotally connected with the bight of the U-shaped part on the exterior face thereof and the base having an arcuate row of holes therein, any one of which is adapted to receive the dog for holding the bar against movement in one direction.

WILLIAM W. STANFIELD.
